COMBINED FIREPLACE SCREEN AND FRAME THEREFOR

Paul H. Casper, Phoenix, Ariz.
(P.O. Box 239, Springerville, Ariz. 85938)

Filed June 10, 1970, Ser. No. 23,416

Term of patent 14 years

Int. Cl. D23—03

U.S. Cl. D23—99

The figure is a front perspective view of a combined fireplace screen and frame therefor showing my new design, the screen being in an open position. The fine mesh in the upper portion of the screen is partially shown for convenience of illustration, it being understood that the mesh is continuous over the area on which it is indicated.

The broken line structure surrounding the frame simulates the brick front of a fireplace for illustrative purposes, and provides an environmental setting for the combined fireplace screen and frame therefor.

The characteristic features of my design reside in the contrasting mesh patterns in the screen front in combination with the hinged screen and frame.

I claim:

The ornamental design for a combined fireplace screen and frame therefor, as shown and described.
